UNITED STATES PATENT OFFICE

ARTHUR DOUGLAS NASH, OF TOLEDO, OHIO, ASSIGNOR TO THE LIBBEY GLASS MANUFACTURING COMPANY, OF TOLEDO, OHIO, A CORPORATION OF OHIO

DESIGN FOR A TUMBLER

Application filed September 2, 1932. Serial No. 44,740. Term of patent 3½ years.

To all whom it may concern:

Be it known that I, ARTHUR DOUGLAS NASH, a citizen of the United States, residing at Toledo, in the county of Lucas and State of Ohio, have invented a new, original, and ornamental Design for a Tumbler, of which the following is the specification, reference being had to the accompanying drawing, forming part hereof, in which:

Figure 1 is a side elevation of the tumbler. Figure 2 is a detail horizontal section through a portion of the tumbler.

The tumbler is preferably made of glass and is transparent. It is provided with vertically extending optic lines due to variations in the wall thickness but is externally of circular horizontal cross-section at all heights.

I claim:

The ornamental design for a tumbler, as shown and described.
